UNITED STATES PATENT OFFICE.

HIRAM BOND, OF HAVERHILL, MASSACHUSETTS.

HEEL-BURNISHING MACHINE.

SPECIFICATION forming part of Letters Patent No. 292,787, dated February 5, 1884.

Application filed December 1, 1883. (No model.)

To all whom it may concern:

Be it known that I, HIRAM BOND, of Haverhill, in the county of Essex and State of Massachusetts, have invented certain Improvements in Heel-Burnishing Machines, of which the following is a specification.

This invention relates to that class of heel-burnishing machines in which the burnishing-tool oscillates in the arc of a circle, and is provided with a yielding movement which enables it to conform to the curvature of a boot or shoe heel.

The object of my invention is to produce a machine of this class in which the burnishing-tool has a continuous rotating movement in addition to the oscillating movement, and also to provide certain improvements in the construction of the tool and its support.

To these ends my invention consists in the improvements which I will now proceed to describe and claim.

Of the accompanying drawings, forming a part of this specification, Figure 1 represents a front elevation of a heel-burnishing machine embodying my invention. Fig. 2 represents a longitudinal section of the tool and its holder.

The same letters of reference indicate the same parts in all the figures.

In the drawings, *a* represents the supporting-standard, in which is journaled an oscillating shaft or arbor, *b*, which is oscillated by a pinion, *c*, on its end, a rack-segment, *d*, meshing with said pinion and formed on a lever, *e*, which is pivoted at *f* to the standard *a*, and a pitman, *g*, connecting the lever *e* with an eccentric, *h*, on a driving-shaft, *i*.

j represents a block rigidly attached to the oscillating shaft *b*, and *k* represents a tool-carrying arm pivoted at *l* to said block, the pivot *l* being at right angles with the shaft *b*, so that the swinging end of the arm *k* can approach and recede from the axial line of said shaft.

m represents a weighted block depending from the arm *k*, and *n* represents a spring attached to the block *j*, and exerting a downward pressure on the weighted block *m*, the swinging end of the tool-carrying arm being thus pressed inwardly toward the axial line of the arbor *b*.

50 The mechanism thus far described is the same that is used in the machine patented to Addy, No. 235,115, of December 7, 1880, and

known to the trade as the "Tapley" heel-burnishing machine, and forms no part of my invention.

Heretofore the tool-carrying arm *k* has had a non-rotating tool adapted to bear on a heel held by the jack *p*, said tool simply oscillating with the block *j*, and bearing with a yielding rubbing pressure against the heel to be bur-

nished.

In carrying out my invention, I provide the tool-carrying arm *k* with a rotary tool, *r*, having a burnishing portion, *2*, a shank, *3*, and a pulley, *4*, all preferably formed in one piece, 65 and provided with a cavity, *5*, which receives a non-rotating stud, *6*, projecting from the arm *k*, the tool being adapted to rotate on said stud. Above the machine I place a swinging frame, *s*, pivoted at *t* to a driving-shaft, *u*, and 70 provided with an arbor, *v*, having a pulley, *w*, belted to a pulley, *y*, on the driving-shaft, and a pulley, *x*, belted to the pulley *4* on the tool *r*. The swinging end of the frame *s* is supported by a spring, *z*, and is connected with 75 the tool-carrying arm *k* by a link, *z'*, which is pivoted to said frame and arm, and causes the frame to conform to the upward and downward movements of the arm, thus keeping taut the belt which drives the tool.

It will be seen that the tool is thus adapted to rotate continuously while it oscillates over the heel. The effect of the machine is therefore much improved in certain kinds of work, such as in burnishing waxed heels—a class of work which heretofore has not been done on the Tapley machine.

The burnishing portion *2* of the tool is preferably ribbed or fluted diagonally on its outer surface.

7 represents a gas-pipe in the stud *6*, projecting into the burnishing portion of the tool for the purpose of heating the latter. At the end of the tool is a vent, *8*, for the escape of the products of combustion and the supply 95 of air.

I claim—

1. In a heel-burnishing machine, the combination, with the oscillating tool-carrying mechanism shown, adapted to conform in its oscillating movements to the shape of a boot or shoe heel, of a rotary tool supported by said carrier and an arbor, and means for rotating the tool while the carrier is oscillating, as set forth.

2. The combination of the block *j*, secured to an oscillating shaft, the tool-carrying arm *k*, pivoted to said block, means for exerting an inward pressure on said arm, a rotary tool pivoted or journaled on said arm, and provided with a pulley, 4, swinging frame *s*, pivoted upon a driving-shaft, and provided with a pulley, *w*, belted to a pulley on the driving-shaft, and with a pulley, *x*, belted to the pulley on the rotary tool, and a link connecting said frame with the tool-carrying arm *k*, and causing the latter to follow the upward and downward movements of said arm, as set forth.

3. The improved tool composed of the burnishing portion 2, shank 3, and pulley 4,

formed in one piece, and relatively arranged as shown, and provided with the longitudinal cavity 5 and vent 8, combined with the non-rotating stud or arbor 6, on which said tool is rotated, and a gas-pipe extending through said arbor into the burnishing portion of the tool, as set forth.

In testimony whereof I have signed my name to this specification, in the presence of two subscribing witnesses, this 24th day of 25 November, 1883.

HIRAM BOND.
